UNITED STATES PATENT OFFICE.

LEWIS L. HEPBURN, OF NEW HAVEN, CONNECTICUT, ASSIGNOR TO THE MARLIN FIRE ARMS COMPANY, OF SAME PLACE.

BREECH-LOADING GUN.

SPECIFICATION forming part of Letters Patent No. 434,062, dated August 12, 1890.

Application filed December 30, 1889. Serial No. 335,467. (No model.)

To all whom it may concern:

Be it known that I, LEWIS L. HEPBURN, of New Haven, in the county of New Haven and State of Connecticut, have invented certain new and useful Improvements in Magazine-Guns, of which the following is a specification.

My invention relates to magazine fire-arms; and it consists in certain new and useful constructions and combinations of the several parts thereof, substantially as hereinafter described and claimed.

In the drawings, Figure 1 is a perspective view of that portion of the gun which contains the operative mechanism with the side plate shown detached. Fig. 2 is a side view of the same, showing the breech open and the carrier raised. Figs. 3, 4, 5, and 6 are views of portions detached; and Fig. 7 is a transverse vertical section on the line $x-x$ of Fig. 2, as it would appear with the side plate B secured in place. Fig. 8 is similar to Fig. 1, except that a portion of the stock and a portion of the carrier are broken away to show the working parts. Fig. 9 is a horizontal section of part of the frame on line $z-z$ of Fig. 7, showing the method of forming and mounting the ejector-spring.

This invention is an improvement upon the fire-arm shown in the Letters Patent granted to A. Burgess, November 19, 1876, No. 210,091, and that of my prior patent, No. 400,679; and its object is to simplify and render more efficient the mechanism thereof, with especial reference to the use of what are known as "No. 22 cartridges;" but many of these improvements will be found valuable in guns of a larger caliber. My present gun differs from that of this Burgess patent in having its opening for ejection of the cartridge-shells at the side instead of the top of the breech-frame, and in having its breech-bolts sustained more firmly by its locking-lever, and in various other details of construction, as herein-after described and claimed, and it differs from the gun of my said former patent in having the breech-block locked by a lever instead of the sliding bolt D of that patent, and in providing a superior form of cartridge-carrier and superior means of operating and controlling the same, and also in various

other details of construction, as hereinafter described and claimed.

A is the frame of the arm, which is formed of a solid block of metal with the recess for the breech mechanism chambered into one side of the same. The barrel C is solidly attached to the front end of this frame, so as to open into the upper part of the recess in the latter. The magazine also opens into this recess below the barrel, being placed underneath and parallel to the latter, as in my said former patent. To the rear part of the frame the stock of the gun is attached. The hammer H is pivoted in the frame in line with the reciprocating breech-block F, so that the backward movement of the latter will set the hammer ready for firing. This breech-block comes out flush with the upper part of the frame, and has its flat upper surface bearing and sliding upon the inner corresponding flat surface of the frame. Underneath the breech-block the recess in the side of the frame is closed by a flat plate B, which forms the guideway on which the breech-block rests and slides on that side. The outer face of plate B, when in place, is flush with the outer side of the breech-block F, and the withdrawal of the breech-block leaves an opening in the side of the frame through which the cartridge-shell is ejected after the gun is fired. One object of this general construction to eject the cartridge sideways from the frame is to avoid the liability of parts of the shell being thrown upward and out of the top of the frame into the face of the person firing the gun. The special purpose of the construction is to give the breech-block a much broader and more extensive frictional bearing-surface on top than was possible with the former construction, where the frame was open on top for the ejection of the cartridge, and the breech-block was supported and guided by small ways and grooves on its vertical sides.

L' is the lever which is used to operate the breech-block to and fro in the frame of the gun, so as to close and open the breech by means of a mortise n^5 in the lower side of the breech-block, into which it enters as its upper end swings upward from the locking

position, and it also locks the breech-block in position for firing, by means of a segmental surface n' on the latter, against which the end of the lever braces when the breech-block is closed, like that of Burgess, the locking-bolt D for that purpose of my said former patent being dispensed with. In order to enable the lever L' to assume a position more nearly in a direct line with the guideways of the breech-block, to form a more effective locking-brace to hold the latter closed during the discharge of the gun, the segmental surface n' on the breech-block, against which the lever takes its bearing to lock the breech, is not located on or in the breech-block, as heretofore, but entirely below the bore of the gun, upon a downwardly-projecting abutment n^2 , extending below its lower surface. By this means I am not only able to bring the lever L' more nearly to a parallel position with relation to the longitudinal axis of the breech-block, but also to pivot it underneath the carrier and in front of the pivot h of the latter, so as to enable it to operate thereon, as hereinafter described, and at the same time serve as an efficient breech-locking brace, without unduly lengthening the frame or working parts of the breech mechanism. Just above and behind the abutment n^2 , and toward the stock of the gun, I provide a mortise n^5 in the lower side of the breech-bolt F, as clearly shown in Fig. 3, into which the upper end of the lever L' enters as it leaves the segmental surface n' , and by engaging with the walls of this mortise it withdraws the breech-block and again brings it up to the barrel on the return-movement of the lever. The breadth of this mortise n^5 should be so proportioned as to allow the lever L to perform its functions in operating the carrier, as hereinafter described.

The lever L L' is pivoted to the frame at l , and has a shoulder l' concentric with its pivot, which takes a bearing against a correspondingly-formed part of the frame when the breech-block is closed, to assist the pivot in resisting the strain of the discharge upon it. This construction of these several parts is superior to that of former constructions in this: That the tendency of the breech-bolt to force back the lever L L' and be opened by the force of the discharge in the former guns was very great, because the comparatively slight breadth of the bearing-surface of the guides in which it ran allowed too great strain to be thrown upon the lever L' , and it was practically impossible to materially increase the breadth of bearing-surface of these guides, because the frame was open at the top to allow the shell to be ejected. It is found, however, that with the frame open at the side for the ejection of the shells the extent of the frictional surface of the frame above it, against which the breech-bolt can be made to hug by the locking-lever L' , is so great that the strain upon the lever from the explosion of the cartridge is greatly relieved, and it is, therefore, practicable to employ the lever for

locking the breech block, thereby greatly simplifying the breech-mechanism of the gun. It is evident that for any given dimensions of frame this advantage will always be had by the present construction.

The next improvement is in the construction of the breech-bolt F with a shoulder n upon the abutment n^2 , which extends down past the floor of the carrier E when the latter is in its elevated position opposite to the mouth of the magazine of the arm, and is adapted to receive the cartridge to be delivered upon the carrier against it, and conduct the cartridge upon the carrier without shock or jar, which might be liable to explode the cartridge. The carrier E is pivoted at h and must be allowed to rise up with the cartridge and remain in that raised position while the breech-bolt moves forward and passes almost or quite through its length to force the cartridge forward into the breech-chamber, because this gun is intended to use very short as well as longer cartridges. The carrier is therefore cut away on one side to allow the depending abutment n^2 , with its shoulder n of the breech-block, to pass by it and come opposite to the magazine, ready to receive the cartridge out of the latter against it when the carrier has dropped down out of the way, as hereinafter described. By this means very short cartridges are prevented from turning and jamming either when being conducted upon the carrier by the breech-block or when being carried off of it into the breech of the gun by the breech-block, while the capacity of the magazine and gun to receive and manipulate long cartridges in transferring them from the magazine to the barrel is not interfered with. Heretofore when any depending portion of the breech-block has been employed to conduct the cartridge upon the carrier it has not been possible to have the latter rise up and hold the cartridge in place while the breech-block with such depending attached portion was moving through it.

Just above the shoulder n on the abutment n^2 of the breech-bolt I provide the bolt on its forward end with a projection i , having a bevel upon its upper edge, Fig. 3, which extends down below the bottom of the floor of the elevated carrier on which the cartridge rests, traversing along past the cut-away part of the carrier with the depending shoulder n , as above described. The beveled projection i serves as the breech-block advances to lift the rear end of the cartridge off from the inclined carrier-bed and raise the axis of the cartridge substantially into line with the bore of the barrel, thus causing the cartridge, especially if a short one, to be pushed into the barrel by the front face of the breech-block while so in line with the barrel and preventing its binding or twisting. This renders the pivoted carrier as effective as one moving vertically up and down in guideways to bring short cartridges into line with the barrel. On the side of the carrier next to the shell-

ejection opening I provide it with a thin wall or lip a , extending up high enough to prevent the shell from escaping by passing over the shell-ejection opening when the carrier is raised to the level of the barrel. On its extreme front end this wall or lip a is cut away to permit the cartridges to be fed over it into the magazine when the carrier is down in the position shown in Fig. 1. In the side plate B , I provide a gate or door, which swings edge-wise downward, as hereinafter described, in a recess in the inner face of the plate, thus avoiding interference with the lip or wall a of the carrier. By these constructions of the several parts I am enabled to retain the cartridges upon the carrier and prevent their escape in an effective manner, while not impairing the capacity of the arm for reloading the magazine.

20. By the new arrangement of the lever $L L'$, I am enabled to carry its pivot l so far back toward the pivot h of the carrier as to dispense with the eccentric on it which was used in combination with the inclined lower surface of the carrier, and to provide the lever with the projection or shoulder l' , which moves concentrically around its pivot and comes in contact with the incline e^2 on the lower face of the carrier, raising the carrier at its free end sufficiently to arrest the succeeding cartridge to the one being conducted onto the carrier by the retiring breech-block at the opening into the magazine. The magazine is constructed under the barrel in the usual manner, 35 and has a spiral spring to push out the column of cartridges as fast as they are removed by the carrier. This employment of the concentrically-moving shoulder l' on the lever, in combination with the bevel e^2 upon the carrier, to raise the latter, as described, is necessary, in order to permit the concentric shoulder l' of the lever $L L'$ to take its bearing supporting the lever in the corresponding recess of the frame; as before described, because this 45 shoulder l' partly occupies the space of the eccentric before used, this bearing-shoulder l' being practically indispensable to the lever when used in locking the breech-bolt, as well as moving it.

50. In practice it is found very convenient, and with guns using small cartridges quite necessary, to be able to readily and quickly get at and clean the breech mechanism of the gun. The shortness of the shells of small cartridges 55 prevents the sealing of the space in the breech-chamber around the shell so effectively as with larger cartridges, and therefore allows the breech mechanism to foul more easily. To get at the breech mechanism readily and quickly, 60 I make the cheek-piece or side plate B of the frame so that it can be removed by hand and without the use of a screw-driver or other tool. Furthermore, as it carries the race or guide way on which the breech-block F runs or bears on one side, I provide one or more shoulders $s^1 s^2$ on or attached to the frame, which project underneath it and support it

accurately in position. The cheek-piece can thus be removed and replaced without impairing its efficiency in supporting the breech-block race. As shown in Figs. 1 and 4, the front end of this plate B is provided with a small projection or lip p , which engages in a correspondingly-shaped under-cut or recess formed in the frame, and it is also provided 75 with a screw or small bolt I , formed with a head projecting outside of plate B and provided with milling or projections thereon, suitable to be grasped and turned by the thumb and finger. This bolt has its body made of 80 such a size that it will slide freely through its hole in plate B ; and near its opposite end, which is provided with a screw-thread to engage in a screw-hole in the opposite wall of the receiver, it has a projection or collar e attached firmly to it, of such a size as will prevent the bolt from being drawn entirely out of its hole in cheek-piece B . Instead of being in the form of a collar, as shown, this projection may be a pin put through the bolt, or of 90 other well-known form, that being immaterial so long as it serves to prevent the bolt from being removed from the plate.

By allowing the bolt to slide for a limited distance outward through the cheek-piece B 95 before it is arrested by projection e it becomes a more efficient handle to pull the plate out of its recess in the frame after the bolt is unscrewed, and the rear end of the plate coming out first the lip p is disengaged by 100 drawing the plate backward. As an aid to the introduction of the plate or cheek-piece B to exactly its proper position, I provide the projections $s^3 s^4$ upon the frame above it to co-operate with projections $s^1 s^2$ below it, and 105 I prefer to employ them, as shown; but they may be omitted, if desired. Instead of the lip p , the front end of plate B may be cut on a bevel and made to engage in a correspondingly-shaped seat in the frame. 110

The carrier is operated by the arm L' of lever $L L'$ by means of a detent or spring-latch o , set so as to move transversely in a recess or slot u , cut in the carrier E , as shown in Figs. 1, 2, 3, and 4, and have the dog or hook of 115 the detent project beyond the face of the carrier and engage with lever L' at the proper time to move the carrier, as hereinafter described. Instead, however, of pivoting the detent loosely in the carrier, as heretofore, 120 and providing it with a rear shoulder for the arm L' to strike against, to set its hook or dog in position to engage with the arm on its return-movement, I now construct it so as to be set in that position by a spring, which 125 presses it against the face of the arm as the latter passes by it. For convenience of construction the recess containing the detent extends back to and around the carrier-pivot h . The rear end of the detent o is provided with 130 a hole fitting loosely over this pivot as it lies in its recess, as shown in Figs. 3 and 5. The other end of the recess is undercut, and the beveled end of the detent extends into this

undercut part to prevent its being forced too far out of the carrier by the spring d , which has a hole fitting over pivot h and lies in the recess behind the detent, pressing it outward, as shown in Fig. 5. The dog or hook c of the detent on its outer face projects outside of the face of the carrier when in its normal position, and is beveled on its outer end part to allow the lever L' to compress it into the 5 detent-recess in the carrier in the act of opening the breech-bolt. By this construction of these several parts—*i. e.*, the carrier and its detent-recess, the detent and its spring—the two latter are held in place by the shoulder 10 of the recess of the frame in which pivot h is located, and swing up and down with the carrier and occupy less space than heretofore, and all screws and pins to fasten them independently are avoided. If preferred, 15 however, the detent and its spring may be secured in the carrier by independent screws or pins, and the advantages of the spring-detent be retained. Instead of a separate spring d , the shank of the detent might itself 20 be made of thin spring metal, and it be fitted on pivot h , so as to dispense with the separate spring. The carrier H is also provided with a fixed pin b , which, being struck by the lever L' , serves to depress it after the cartridge has 25 been delivered into the barrel out of it. The lever L' is modified to cause it to operate with the dog c of the detent differently from my previous invention, as follows: In the first 30 part of its forward movement to close the breech-block the front side of the lever L' engages with the dog c of detent o and throws the carrier upward before it engages with the breech-block. Just at the moment that the upper end of the lever L' begins to engage 35 with the forward wall of mortise n^5 of the breech-block the slot or recess c^2 in the face of the lever next the dog c arrives opposite to the dog and allows the latter to enter it, the carrier being then raised to its highest 40 limit. This slot or recess c^2 is made so as to hold the carrier in this raised position by its lower edge taking a bearing against the lower side of the dog, and the carrier is thus positively kept in its raised position during a considerable portion of the traverse of the breech-block through or along its upper surface before the dog passes out of the slot c^2 . This 45 construction enables the breech-block to push forward shorter as well as longer cartridges out of the carrier with equal certainty, since the carrier is not allowed to drop down as soon as it reaches the slot, as in my said former patent. The spring d of detent o aids in effecting this action, and by pressing the dog 50 c against the face of lever L' after the dog has left slot c^2 continues to hold the carrier up until the lever comes in contact with the pin b of the carrier and throws it down after the breech-block has been pushed clear home 55 against the breech.

To prevent all liability of the cartridge being tipped up and displaced on the carrier,

particularly if it be short, before or when the carrier is being raised, I provide yielding or spring partition P , which is located in the side 70 plate B and extends parallel with the breech-block, projecting horizontally and transversely underneath the latter into the space through which the carrier rises in transferring the cartridge to the barrel. When the 75 breech-block is being withdrawn, this partition retains its normal position until the carrier, with the cartridge on it, rises and presses upon its lower inclined beveled face. Meantime this partition projects far enough into 80 this chamber toward the opposite wall of frame A to prevent the cartridge from passing between itself and that wall by any springing or bounding of the cartridges upon the carrier, and thus keeps the cartridge from escaping after the breech-bolt is drawn back 85 and before the carrier is raised, or from assuming any other than its normal horizontal position on the carrier. When the carrier is rising up to transfer the cartridge to the barrel 90 brings the pressure of the cartridge upon the lower inclined beveled face of partition P , it pushes the latter to one side and allows the cartridge and carrier to pass by it far enough to bring the cartridge opposite the 95 bore of the barrel. On the descent of the carrier the partition springs back to its normal position. It is so located that a cartridge cannot turn up endwise beneath it after being received from the magazine upon the carrier. 100

The partition P is attached to one end of the flat spring m , the other end of which is fixed by a screw in the recess of the plate B , as shown in Fig. 4, and the lower edge of the partition is beveled off, as shown in Fig. 7, 105 so as to allow the cartridge and face of the carrier to press it to one side and pass by it when lifted by the carrier, the recess behind it being deep enough to permit of this. This partition might have its spring arranged in 110 other ways, if desired—as, for instance, behind it, with the same effect.

An opening is made through the side plate B for introducing the cartridges into the magazine, and on the inside of the plate a gate T is hung upon a spring r , so as to move edge-wise to insert the cartridge, the plate being recessed properly to allow of this. The upper edge of the gate T is beveled off on its outer face next plate B for its entire length, as 115 shown in Figs. 1 and 7. By pushing the point of the cartridge against this bevel the gate will be thrust aside, no matter where on the bevel it happens to strike, for the point of the cartridge will always travel along the bevel until it reaches the end nearest the magazine, being guided by the bevel. To aid the bevel on the gate, a bevel is also made on the upper outer edge of the opening in plate B , so that it forms a V shape with the bevel on the gate 120 when the latter is closed. This enables the point of the cartridge to be more readily brought against the bevel on the gate. 125

The extractor is of the spring-hook variety,

but is secured to the breech-bolt F in a novel manner. As shown in Fig. 6, a groove is milled or cut in the top of the bolt for about half its length at a point just in line with the 5 right-hand wall of the chamber, or nearly so, and of sufficient depth to permit the extractor t to be set therein and have its hook come opposite the right-hand side of the cartridge-head. This extractor t is made with a solid 10 shank of the proper size to fit snugly in the recess in position to hold the spring-hook end of the extractor properly to engage with the cartridge-head by the action of the opposite solid walls of the recess upon the shank. This 15 is due to the fact that the walls of the recess bear snugly upon the shank of the extractor on the same side as its hook, and on the opposite side thereof for a certain distance from the heel of the shank, and the spring part of 20 the extractor is thinned down from thence toward its hook end, so as to allow the proper movement of the spring end in the groove for its hook to spring over the cartridge-head. The solid walls of the breech-bolt thus take 25 all the strain brought upon the shank of the extractor, and there are no holding-screws to come loose or wear out. On one side of the shank is a projection w, which fits in a corresponding recess formed in the side wall of 30 the long recess, as shown, and which serves to lock the extractor in place and prevent it from being pulled endwise out of its seat when extracting the shell. The extractor thus made is simply set in the recess without other fastening, it being prevented from rising by the 35 top wall of the frame when the breech-bolt is in position, but being free to be lifted out when the bolt is detached. By this construction I avoid the use of any pin or screw, and 40 am enabled to remove the extractor, whenever desired, by the thumb and finger and without the use of a tool.

The form of the spring-ejector claimed in my said former patent is improved especially 45 to adapt it for short cartridge-shells and cause it to throw them out more certainly, although it is better for longer ones also. In front of the shoulder z², which is made right-angled the same as before, I provide a curved 50 nose z³, which extends outward in front of the shoulder and reaches around the cartridge-head and strikes the shell between the head and open end of the same on its side. This is effected by making the notch in the ejector 55 between the shoulder z² and the nose z³ deep enough to allow the head of the cartridge to enter it as the ejector springs forward, and thus allow the force of blow of the ejector upon the shell to be delivered first by the 60 nose z³ before it strikes the side of the head of the cartridge. The head of the cartridge being at the same time held by the extractor-hook t, the backward movement of the breech-bolt brings the opposite side of the cartridge-head against the shoulder z² and tends to 65 throw the shell forward toward the open end of the barrel as well as outward, (giving it a

rotary motion in a horizontal plane,) and but for the nose z³ of the ejector the shell would frequently strike the end of the barrel and 70 lodge there. This nose, however, striking the side of the shell, as before described, turns its other end outward so quickly that it never fails to clear the end of the barrel and be thrown outward properly. This gives the 75 shell a more direct sidewise motion and sends it clear of the breech-chamber with greater certainty.

In order to prevent the gun from being fired before the breech-block is locked by the 80 lever L', I provide a guard-spring 1, which bears upon the trigger 2 when in its normal position below the pivot 3, on which the latter is hung. The sear or nose piece 4 of the trigger is hung upon the same pivot, so that 85 the trigger 2 has a slight movement of that part to allow the end of spring 1 to pass behind it. On spring 1 is fixed a stud 5, which projects downward through the frame into the path of arm L of lever L' L'', so that during the last part of its movement when it is locking the breech it shall come in contact with this stud at its other end and lift the free end of spring 1 from behind the trigger, allowing the latter to be operated to 90 fire the gun. The frictional bearing of the end of part L' of the lever against the breech-bolt is very useful in keeping the part L of the lever pressed up against the stud 5, so that the trigger may remain unlocked and 95 ready for firing, as described, such frictional bearing being so far from the pivot l of the lever. To aid in holding the lever L' L'' in this closed position, I have provided a spring 6, the nose of which enters the notch 7 on the 100 periphery of the hub of the lever when the latter is closed. The nose of the spring is rounded and springs out of the notch when the lever L is carried forward to unlock the 105 breech.

It is evident that by providing the breech-bolt with the segmental locking-surface n', and pivoting the lever L underneath the carrier and between the pivot of the latter and its free end I am enabled to allow the carrier 115 to remain down opposite the magazine during the backward motion of the lever, which unlocks and withdraws the breech-block and conducts the cartridge upon the carrier, and on the return-movement of the lever to both raise and 120 depress the carrier while the breech-block is moving forward and being locked by the lever, and that this double movement of the carrier during one movement of the lever is due to the position of their pivots to each other, as 125 described, and of the segmental locking-surface n'. Furthermore, not only is this true generally of the movements of these parts, but the location of the segmental locking-surface n' on an abutment depending below the line 130 of bore of the barrel gives to the lever L' a greater amount of sweep and movement in which to actuate and hold up the carrier and deliver the cartridge to the barrel before the

breech-block is locked, and thereby increases the certainty of handling the cartridge, as well as the locking-power of the lever against segmental surface n' .

5. By the above-described improvements I am enabled to produce a gun of superior breech mechanism, which handles the cartridges so certainly and perfectly in transferring them from the magazine to the barrel and ejects 10 the shells so certainly that small cartridges—like No. 22—can be used with it as well as larger ones. It will also automatically handle and take care of cartridges of different lengths as well as those of the same length, 15 even where the former are mixed indiscriminately in the magazine.

What I claim as new and of my invention is—

1. The combination of barrel C, frame A, 20 closed at the top and provided with its opening for ejecting the shells in its side, breech-block F, provided with the segmental surface n' and a mortise in its lower side, and having its flat upper face bearing and sliding against 25 the corresponding inner face of the closed frame top, and the locking-lever L' , pivoted in the frame beneath the breech-block and arranged to bear against said segmental surface at an angle to the upper face of the breech-block and lock the latter against the breech, 30 substantially as described.

2. The combination of barrel C, frame A, attached thereto, the breech-block arranged to travel reciprocally on guideways in said 35 frame to and from the breech, provided with a mortise in its lower side, and the segmental surface n' , located upon a depending abutment or projection entirely below the line of the bore of the barrel, and the lever L' , pivoted in the frame below the breech-block and 40 arranged to enter said mortise and move the latter and to take its bearing against said segmental surface and lock the breech-block to the breech, substantially as described.

45 3. The combination of barrel C, frame A, attached thereto, the magazine beneath the barrel opening into the frame, the breech-block arranged to travel reciprocally on guideways in said frame to and from the breech, provided with a mortise in its lower side, and 50 with the depending abutment n^2 , having the segmental surface n' on one face thereof, and the shoulder n opposite to the magazine on the opposite face thereof, and the lever L' , pivoted in the frame below the breech-block and 55 arranged to enter said mortise and move the latter, and to take its bearing against said segmental surface and lock the breech-block, substantially as described.

60 4. The combination of barrel C, frame A, attached thereto, the magazine beneath the barrel opening into the frame, the reciprocally-moving breech-block F, provided with a mortise and the segmental shoulder n' on the lower side thereof, and also with the shoulder n , depending opposite to the magazine, and the carrier E, moving in a vertical plane, 65

arranged to allow the breech-block to traverse longitudinally through it in forcing the cartridge into the barrel, and having one side 70 cut away to allow the said depending shoulder n to pass by it while in that position, substantially as described.

5. The combination of frame A, provided with a side opening for the ejection of cartridge-shells, and with an opening beneath it for inserting cartridges into the magazine, and the carrier E, moving in a vertical plane, provided with a wall or lip arranged to cover the shell-ejection aperture when the carrier 80 is raised and prevent the escape of cartridges through the same, and to descend below the cartridge-inserting aperture and allow the cartridges to be inserted therein over it when the carrier is lowered, substantially as described. 85

6. The combination of frame A, provided with a side opening for the ejection of cartridge-shells, and with an opening beneath it for inserting cartridges into the magazine, the carrier E, moving in a vertical plane, provided with a wall or lip arranged to cover the shell-ejection aperture when the carrier is 90 raised and prevent the escape of cartridges through the same, and to descend below the cartridge-inserting aperture and allow the cartridges to be inserted therein over it when the carrier is lowered, and the gate T, covering the said cartridge-inserting aperture and 95 arranged to swing away from the same edge-wise, substantially as described.

100 7. The combination of the barrel, the magazine located on a plane below it, the frame A, connected thereto, the pivoted carrier arranged to receive the cartridge thereon from the magazine and elevate the point thereof to the level of the barrel, the reciprocating breech-block arranged to traverse along the upper side of the carrier and carry the cartridge into the barrel, provided at its front end with the incline i , adapted to pass under the rear end of the cartridge upon the carrier 105 and elevate the same against the front end of the breech-block as the latter moves forward, and mechanism adapted to operate the carrier and breech-block, substantially in the 110 manner and for the purposes described. 115

8. The combination of the barrel, the magazine located underneath the same and opening rearward, the frame A, connected to said barrel and magazine, the pivoted carrier E, 120 hung to present its free end to the magazine and barrel and transfer the cartridge from one to the other, the reciprocating breech-block F, provided with the incline i on its front end, arranged to pass under the rear end 125 of the cartridge on the carrier and elevate it against the front end of the breech-block, and the lever L' , adapted to move the carrier and breech-block by means of suitable shoulders or stops on the latter, substantially in the 130 manner and for the purposes described.

9. The combination of the magazine, the breech-block, provided with the depending shoulder n opposite to the magazine, and with

a mortise in its lower side, the carrier E, provided with the incline e^2 on its lower edge, and the lever L', provided, with the concentric shoulder l' bearing against frame A, and the concentrically moving shoulder l^2 , arranged to pass under the incline e^2 and lift the free end of the carrier opposite to the magazine before the end of the lever has moved the breech-block and its shoulder n backward, together with the cartridge resting against the shoulder, whereby the carrier is placed in position to stop the next succeeding cartridge in the magazine until the shoulder n is returned to arrest it, substantially as described.

10 15 10. The combination of the frame A, containing the breech mechanism, the reciprocating breech-block moving therein on guide or race ways, and the removable side plate B, having a portion of it forming one of said 20 raceways supporting the breech-block, substantially as described.

11. The combination of frame A, containing the breech mechanism and provided with shoulders s^1 s^2 projecting laterally therefrom, the reciprocating breech-block moving therein 25 on guide or race ways, and the removable side plate B, having a portion of it opposite to said shoulders when it is attached to the frame forming one of said raceways supporting the 30 breech-block, substantially as described.

12. The combination of frame A, containing the breech mechanism and provided with shoulders s^1 s^2 s^3 s^4 projecting laterally therefrom, the reciprocating breech-block moving 35 in the frame on guide or race ways, and the removable side plate B, fitting between and sustained by said projections and having a portion of it forming one of said raceways, substantially as described.

40 45 13. The combination of the carrier E, pivoted at its rear end and provided with the spring-dog c , beveled on its front face and projecting from the inner face of the carrier, and the lever L', pivoted below the carrier and provided with a transverse slot c^2 across its face adjacent to said carrier, so formed as to sustain the carrier in its position while the dog traverses it during the forward movement of the lever to close the breech, substantially as 50 described.

55 14. The combination of the carrier pivoted at its rear end and provided with the yielding dog c , and the fixed pinion b , projecting from its inner face, and the lever L', pivoted below the carrier and provided with a transverse slot c^2 across its face adjacent to said carrier, so formed as to sustain the carrier in its position when the dog traverses it during the forward movement of the lever to close 60 the breech and to allow the latter to strike the pin b and depress the carrier after the dog has passed out of the slot, substantially as described.

65 15. The combination of the barrel C, the magazine, the frame A, attached to the barrel and magazine, the breech-block arranged to travel reciprocally on guideways in said

frame to and from the breech, provided with a mortise in its lower face and the segmental locking-surface n' , located entirely below the 70 line of bore of the barrel, the carrier E, moving in a vertical plane, arranged to convey the cartridge from the magazine to the barrel, and provided with shoulders or pins projecting therefrom, and the pivoted lever L, 75 arranged to strike against the pins or shoulders on the carrier and operate the same and to take a bearing upon the said segmental surface and lock and unlock and move the breech-bolt, substantially as described. 80

16. The combination of the barrel C, the magazine, the frame A, attached to the barrel and magazine, the breech-block arranged to travel reciprocally on ways in said frame to and from the breech, provided with a mortise 85 in its lower face, and the segmental locking-surface n' , the carrier E, pivoted at its rear end and presenting its front end to the magazine and barrel in position to transfer the cartridge from one to the other, and provided with 90 shoulders or projections in its face, and the lever L', pivoted in the frame beneath the carrier between its pivot and free end and arranged to engage with said projections and operate the carrier and to engage with said 95 mortise and segmental surface n' and move and lock the breech-block, substantially as described.

17. The combination of the barrel, the magazine located on a plane below it, the frame A, 100 connected to the magazine and barrel, a rising and falling carrier located in said frame and arranged to elevate the cartridges from the magazine to the barrel, and a longitudinal yielding partition l^3 , projecting on a plane between the magazine and the bore of the barrel from one side of the frame into the space traversed by the carrier and arranged to arrest the independent movement of the cartridge on the carrier and to yield and allow them to pass upward opposite the bore of the barrel, substantially as described. 105

18. The combination of the barrel C, the magazine located underneath and below it, the frame A, having the magazine and barrel opening into it, the pivoted carrier E, arranged to raise the cartridge from the magazine to the barrel, and the longitudinal yielding partition l^3 , located in a recess in the side plate of the frame and arranged to project 115 into the latter and arrest the independent movement of the cartridge on the carrier and to yield and allow the latter to carry the cartridge past it, substantially as described. 120

19. The combination of the frame-plate B, 125 having an opening through it for the introduction of cartridges, and the gate T, arranged to move edgewise from over said opening and provided with a bevel along that entire outer edge which passes across said opening adapted to receive the point of the cartridge and guide it to the end thereof nearest to the magazine, substantially as described. 130

20. The combination of the frame-plate B,

having an opening through it for the introduction of cartridges with the outer longitudinal edge of said opening beveled off, and the gate T, arranged to move edgewise from over said opening and provided with a bevel along its corresponding longitudinal edge which passes across said opening, arranged to form a V shape with the bevel of the latter and receive and guide the point of the cartridge when the latter is inserted into the opening, substantially as described.

21. The spring-ejector provided with the projection i^2 , having a right-angled face at its front end and an inclined or beveled face at its rear, and also provided with the curved nose i^3 , projecting in front of shoulder i^2 , and adapted to strike the body part of the cartridge-shell as its head is caught against shoulder i^2 and project it sidewise out of the gun, substantially as described.

22. The combination of the trigger 2 and its nose 4, hung on the pivot 3, the guard-spring 1, arranged to engage behind the trigger and provided with the stud 5, projecting below the frame, the breech-block F, provided with the segmental locking-surface n' , and the lever L L', having its upper end arranged to engage frictionally with the segmental surface and lock the bolt, while its lower end presses against stud 5 and releases the trigger, substantially as described.

23. A gun receiver or frame having its side plate detachable, said plate being provided with a thumb-bolt for holding it in place, and said thumb-bolt being provided with a collar or projection inside of the plate, substantially as described, whereby the withdrawal of the bolt will serve to remove the plate.

24. A reciprocating breech bolt or block for a gun, provided at its front end with an inclined projection i , adapted to pass under the

head of the cartridge and raise it to the proper position to enter the chamber of the gun, substantially as described.

25. The combination of the frame of the arm provided with the pivot h , the carrier E, provided with a recess extending longitudinally forward from and around said pivot, and the detent o and its spring d , mounted in said recess on the pivot and turning thereon with the carrier, substantially as described.

26. In a magazine-gun, the carrier moving in a vertical plane and the yielding partition l^3 , projecting into the space through which the cartridge moves between the magazine and barrel and arranged to prevent the cartridge from tipping up or escaping from the carrier, and to yield and allow the cartridge to pass by it when lifted by the carrier, substantially as described.

27. In combination with a reciprocating breech-bolt for a gun, the spring-hook extractor t , set in a longitudinal recess or groove cut in said bolt in position to hold the shank of the extractor against the strain of its elastic-hook end (in the act of engaging the cartridge) by the opposite solid walls of said groove, the said extractor being held against longitudinal movement in said groove by an enlargement arranged to fit in a corresponding recess in the bolt, substantially as described.

28. The carrier E, provided with a vertical lip a , arranged to come opposite the opening in the side of the frame as the breech-bolt recedes, for the purpose of preventing the cartridge from falling out, as set forth.

LEWIS L. HEPBURN.
